BOLT CLOSER FOR AUTOMATIC ARMS

Gino Revelli, Rome, Italy; vested in the Alien
Property Custodian

Application December 12, 1939, Serial No. 308,845
In Italy December 21, 1938

2 Claims. (Cl. 42—4)

This invention relates to an improved breech block operating means for automatic firearms and has for its object the provision of means permitting the retraction of the breech block at a relatively low pressure thereby resulting in reduction of friction, wear of the parts and strain to which the parts are subjected.

The invention relates to a firearm of the type wherein a breech block casing or barrel extension is locked to the breech block for a short portion of the recoil stroke; the barrel and breech block moving backward together during such portion of the recoil.

The invention consists in an improved automatic firearm of the type referred to, characterized in that the barrel extension and breech block are locked together by an oscillating pawl one end of which seats in a recessed part of a barrel extension while the other end engages in a notch in the block, the said pawl being locked in engaging position by one arm of a bell crank lever, the other arm of which engages a fixed stop during the recoil stroke.

The invention further consists in providing the pawl with a downwardly extending part designed to engage the first mentioned arm of the bell crank lever only when said lever has completed a predetermined angular movement.

Other objects of my invention will appear from the following description taken in connection with the accompanying drawings wherein,

Fig. 1 is a partial longitudinal sectional view, partly in elevation, of a portable rifle, with a cartridge in the barrel, blocked therein by the bolt or breech block and with the striker cocked ready for firing.

Fig. 2 is a similar view with the parts in the position they assume during the extraction of the cartridge case.

Fig. 3 is a similar view with the parts in the position they assume after firing and extraction of the cartridge case.

Figs. 4 and 5 are enlarged detail views of portions of the structure shown in Figs. 1 and 2 respectively.

Referring to Fig. 1, the barrel 1 is screwed to the breech casing 2 and held in the position shown by a spring 20. Against the back of the barrel 1 bears the breech block or bolt 3 held in this position by a pawl 4, the forward portion 5 of which as shown in Fig. 1 is seated in a recess 6 in the under surface of the bolt 3. Inside the bolt 3 is the striker 7 which is adapted to be actuated by a spring (not shown) acting through the rod 8.

The rear surface 9 of the pawl 4 is cylindrical and is seated in a recess 10 in the movable breech casing, the pawl being adapted to turn in seat from the position shown in Fig. 1 to that shown in Fig. 2. The pawl is formed with a downward extending curved portion 11 adapted to co-operate with the upper arm 12 of a bell crank lever 12—13 pivoted at 14. In the blocked position shown in Fig. 1, the lever 12—13 holds with the end of its arm 12 the blocking pawl 4 in the recess 6, this arm 12 engaging the lower surface 15 of the pawl. The lever 12—13 is biased to the position shown in Fig. 1 by a spring 16.

At the instant of firing the case 17 reacts 15 against the bolt 3 moving it and its contained striker backward and due to the locking action of the pawl 4, the barrel and bolt move backward as a unit. Due to the relatively great mass of the barrel, barrel extension and bolt this initial backward movement is comparatively slow with the result that an increased speed of the bullet is obtained.

After a certain distance is traversed in the recoil movement, arm 13 of lever 12—13 engages 25 against the fixed stop 18 and moves the lever in a counter-clockwise direction against the action of the spring 16. The end of the arm 12 slides on the surface 15 of the pawl 4, then leaving the surface enters the notch 19 between the pawl proper and the extension 11. The arm 12 then engages the upper surface of the extension 11 and lowers the latter and pawl. This lowering movement is progressively accelerated since the initial engagement of arm 12 and extension 11 30 is between the inner part of arm 12 and the outer end of the extension and later the outer end of the arm engages the inner portion of the extension.

When the locking pawl 4 has left the seat 6 40 in the under surface of the bolt 3 the latter, together with the striker due to the reaction of the shell case 17, moves backward independently of the breech block casing and through rod 3 compresses the thrust spring, and assumes the 45 position shown in Fig. 3.

Starting from the position shown in Fig. 3 the bolt 3 is pushed forward by the thrust spring acting through the rod 8 and in such movement engages the upper cartridge 21 of the magazine 50 and thrusts it into the chamber 23. The advance of the bolt and the striker take place together until the back of the tooth 24 of the striker engages the seat 25. The striker is then stopped in its advance while the bolt continues due to 55 inertia, thrusting the cartridge into the appro-

priate space in the barrel. The parts are now returned to the position shown in Fig. 1.

To prevent impinging of the striker against the cartridge cap before closure by the bolt has been completed, there is provided a safety lever 26 one end 27 of which co-operates with the arm 13 of the bell crank lever while the other end 28 engages the tooth 24 of the striker 7 when the bell crank lever is disengaged from the pawl. In this way until the pawl is snapped into the notch 6 in the bolt and consequently the lever 12-13 is returned to the position of Fig. 1 any untimely movement of the trigger 29 cannot fire the cartridge because the striker is held back by engagement of the end 28 of the safety lever 15 engaging the tooth 24.

A spring 32 urges the safety lever 26 to a position for engagement with the tooth 24 on the forward movement of the bolt. The parts are so proportioned that the lowering of the lever 26 takes place at the instant when pawl 4 engages in the notch 3 of the bolt 6.

Having now described my invention, what I claim and desire to secure by Letters Patent is:

1. An automatic firearm comprising a barrel 25 having a rear extension rigid therewith and

formed with a recess, a bolt having a notch in its surface, an oscillating pawl, one end of which is pivotally mounted in said recess, and the other end which is adapted to engage in said notch to lock said extension and bolt together, a bell crank lever pivoted on and movable with said extension, one arm of said lever being constructed and arranged to engage said pawl to lock the same in locked position, a fixed stop adapted to engage the other arm of said lever during recoil movement, said pawl being formed with a downward extension adapted to be engaged by said first named arm when said lever has completed a pre-determined angular movement, to remove said pawl from said notch and means biasing said lever and pawl to locking position.

2. The firearm as claimed in claim 1 wherein the bolt is provided with a striker, and an automatic safety lever is pivotally mounted on said extension biased to position to lock said striker and actuated by said bell crank lever to unlock said striker when said bolt is locked to said barrel extension.

GINO REVELLI.
